UNITED STATES PATENT OFFICE.

GEORGE J. DEHN, OF CHICAGO, ILLINOIS.

FLOOR-DRAIN.

1,123,705.

Specification of Letters Patent.

Patented Jan. 5, 1915.

Application filed December 16, 1912. Serial No. 736,945.

To all whom it may concern:

Be it known that I, GEORGE J. DEHN, a resident of Chicago, in the county of Cook and State of Illinois, have invented certain new and useful Improvements in Floor-Drains, of which the following is a full, clear, and exact description.

The invention relates to floor drains.

In practice, when the floor drains or basins are placed in a concrete floor, it has been found that, as a result of imperfect construction or slight sagging of the floor or from other causes, the basin in many instances, becomes loose in the concrete and rises above the floor, so that water will leak around the outside of the basin and through the floor.

The present invention designs to provide means for anchoring the drain-receiver in the concrete with a suitable water-tight joint between the concrete and the bowl, and so that the basin will be firmly embedded in the concrete and held against upward displacement in the floor.

The invention consists in the several novel features hereinafter set forth and more particularly defined by claims at the conclusion hereof.

In the drawings: Figure 1 is a sectional perspective of a floor drain embodying the invention. Fig. 2 is a horizontal section taken on line 2—2 of Fig. 1. Fig. 3 is a detail of the ring for holding the packing against the basin.

The floor-drain comprises a bowl or basin 10 suitably connected to a vertical pipe 11 containing a back water valve 12, a chamber 13 being formed between the upper end of pipe 11 and basin 10 to contain a body of water. The top 14 of the basin is flush with the top of a concrete floor 15 and is provided with a removable cover 16 which has perforations therein to permit the drainage to pass into chamber 13 of the basin. A trap-bend 17 is adjustably connected to pipe 11 by a collar 30 and packing 31, contains a water-seal 18, and is connected to the discharge terminal 19. The parts thus far described may be of usual or well known construction, and are designed to receive the drainage, form a water-seal, provide a back-water valve, and conduct the drainage to the sewer. This basin is detachably connected to pipe 11 by a slip and interlocking

connection 10^a, such as set forth in Letters 55 Patent No. 935,000 granted to me, Sept. 28, 1909.

In practice, drainage-basin 10 is usually formed with its side curved inwardly and downwardly or tapered inwardly and downwardly. The basin has a series of lugs 20 which project laterally from the outside near the bottom thereof. An anchor comprising a ring 21 is supported on lugs 20 when the concrete is being laid, this ring 65 being provided with notches 22 which are adapted to permit the ring 21 to be slipped into position above the lugs and then turned to cause the lugs to support the ring. Prongs or arms 23 are formed on the ring to 70 extend some distance from the basin, so that the anchor ring will be secured in the concrete by having portions thereof extending outwardly from the bowl, where the concrete will be tamped or packed in being 75 laid. In practice, it occurs that workmen sometimes neglect to pack or tamp concrete around the lower portion of the basin. The inner portion of ring 21 is formed with an inclined seat 24 for a packing ring 25 which 80 usually consists of a cable or strip of asbestos or oakum. A ring 27 is adapted to be secured to an anchor-ring 21 by bolts 28 and is provided with an inclined flange 29 whereby packing-ring 25 will be pressed 85 against seat 24 on ring 21, and forced inwardly to engage the outside of basin 10. Slipping of the packing ring 25 between the ring members 21 and 27, so that a portion of the packing ring projects beyond 90 the inner edge of said ring, provides an expandable joint for the anchoring means. Resultantly, when the bowl is set in the concrete with an imperfect joint between the concrete and the side of the bowl, packing 95 ring 25 which is securely held between the anchor ring 21 and the retaining ring 27 will prevent any leakage around the bowl and through the floor. Aside from serving to hold the packing, the anchor-ring when 100 the concrete has become set, rigidly secures the basin against becoming loose or moving upwardly relatively to the floor, so that the anchor will serve to firmly retain the basin in the floor and not permit it to work 105 loose, and will particularly secure the basin against upward movement in the floor, which is a desideratum in drains for con-

crete floors. Furthermore, the basin serves to support the anchor, while the floor is being laid.

It will be understood that the anchoring-device will be slipped onto and connected to the basin before the latter is placed on pipe 11 or before said pipe is secured in trap-bend 17. This construction makes it possible to employ an integral floor-flange 14 and when the basin is to be used in a floor where no anchoring device is desired, the anchoring device may be omitted.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. A floor drain comprising a receiver-basin, a discharge pipe connected to said basin, anchoring means on the outside of the basin adapted to be embedded in a concrete floor to secure the basin in the floor packing between the anchoring means and the outside of the basin and means on the anchoring means for pressing the packing inwardly against the outside of the basin.

2. A floor-drain comprising a receiver-basin, a discharge-pipe connected to said basin, packing around the basin, and means adapted to be held in the surrounding concrete of a floor for holding said packing.

3. A floor drain comprising a receiver-basin, a discharge pipe connected to said basin and anchoring means around the basin adapted to be secured in a concrete floor and comprising a pair of rings connected together and packing between said rings.

4. A floor-drain comprising a receiver-basin, a discharge pipe connected to said basin, anchoring-means adapted to be embedded in a concrete-floor, and a slip and interlocking connection between the anchoring-means and the basin.

5. A floor-drain comprising a receiver-basin, a discharge pipe connected to said basin, anchoring-means around the basin adapted to be secured in a concrete floor,

and comprising a ring, and an interlocking connection between said ring and the outside of the bowl.

6. A floor-drain comprising a receiver-basin, a discharge-pipe connected to the bottom thereof, an anchoring device supported by said basin and adapted to be embedded in a concrete floor around the bowl and to secure the basin in the floor, packing between the anchoring means and the outside of the basin and means on the anchoring means for pressing the packing inwardly against the outside of the basin.

7. A floor-drain comprising a receiver-basin, a discharge pipe connected to said basin, an anchoring device around the basin adapted to be embedded in a concrete floor, means on the basin for engaging said device to support it before the floor is laid, and packing between said anchoring-device and the outside of the basin.

8. A floor-drain comprising a receiver-basin, a discharge-pipe connected to said basin, an anchoring-device around the basin, means on the bowl for supporting said device before the floor is laid, packing between said device and the outside of the bowl and a ring secured to said anchoring device for holding the packing.

9. A floor-drain comprising a receiver-basin, a discharge pipe connected to said basin, a series of lugs on the outside of the bowl, an anchoring-device comprising a ring having notches through which the lugs may pass, prongs on the ring, a ring removably secured to the notch ring and packing between said rings.

10. A floor drain comprising a receiver-basin, a discharge pipe connected to said basin, an anchoring device, comprising a ring having outwardly extending lugs around the basin, adapted to be secured in a concrete floor, and an interlocking connection between said ring and the outside of the bowl.

GEORGE J. DEHN.
